UNITED STATES PATENT OFFICE.

BERTRAM A. SEGAR, OF NEW YORK, N. Y., ASSIGNOR TO THE SEGAR STUDIOS INC., A CORPORATION OF NEW YORK.

DESIGN FOR A LIGHTING-FIXTURE PART OR SIMILAR ARTICLE.

Application filed January 31, 1924. Serial No. 8,487. Term of patent 7 years.

To all whom it may concern:

Be it known that I, BERTRAM A. SEGAR, a subject of the King of Great Britain, and a resident of the city, county, and State of New York, have invented a new, original, and ornamental Design for Lighting-Fixture Parts, or Similar Articles, of which the following is a specification, reference being had to the accompanying drawing, forming a part hereof.

Fig. 1 is a plan view of the lighting fixture part, or similar articles, and Fig. 2 is a cross section taken on the line 2—2 of Fig. 1.

I claim:

The ornamental design for a lighting fixture part, or similar article substantially as shown.

BERTRAM A. SEGAR.
